UNITED STATES PATENT OFFICE.

JOSEPH T. BAILEY, OF PHILADELPHIA, PENNSYLVANIA.

DESIGN FOR A BADGE.

SPECIFICATION forming part of Design No. 28,256, dated February 8, 1898.

Application filed November 10, 1897. Serial No. 658,102. Term of patent 14 years.

To all whom it may concern:

Be it known that I, JOSEPH T. BAILEY, a citizen of the United States, residing in the city and county of Philadelphia, State of Pennsylvania, have invented and produced a new and original Design for Badges, of which the following is a specification, reference being had to the accompanying drawings, forming part thereof.

10 The leading feature of my design for a badge is a rosette having a field of segments and a line of loops radiating from the center thereof.

Figure 1 represents a face view of a badge embodying my design. Fig. 2 represents a 15 section thereof on line xx , Fig. 1. Fig. 3 represents a side elevation thereof.

In the drawings, A designates a rosette or

head having a circular field consisting of the segments B in folds, the band C at the center of said fold, and the lines of loops D, which 20 radiate from said center. The field is inclosed by the rim E.

The colors of the badge are contrasting, but will be those of the Continental army, of which the badge is a commemoration. 25

Having described my invention, what I claim as new, and desire to secure by Letters Patent, is—

The design for a badge, substantially as described and shown.

JOSEPH T. BAILEY.
